UNITED STATES PATENT OFFICE.

HARRY W. BOLENS, OF PORT WASHINGTON, WISCONSIN.

MAKE-AND-BREAK IGNITER.

1,073,087.

Specification of Letters Patent Patented Sept. 16, 1913.

Application filed June 28, 1912. Serial No. 706,451.

To all whom it may concern:

Be it known that I, HARRY W. BOLENS, a citizen of the United States, and resident of Port Washington, in the county of Ozaukee 5 and State of Wisconsin, have invented certain new and useful Improvements in Make-and-Break Igniters; and I do hereby declare that the following is a full, clear, and exact description thereof.

10 My invention refers to igniters of the make and break type for gas engines, its object being to provide a simple, economical, durable and effective means in connection with the link or rod for actuating the movable electrode and also to provide an adjustment of said actuating means with relation to its carrying rod whereby the instant of 15 sparking is timed, the invention being embodied in an igniter trip-pawl and its means 20 of attachment.

The construction and arrangement of my invention is such that the trip-pawl is fulcrumed and nested within a skeleton housing, which housing is adjustably secured to 25 the valve-rod by a single bolt and is provided with an auxiliary support or stop in connection with said rod whereby twisting strain upon the pivot-bolt is relieved and the proper position of the engaging nose of 30 the pawl is maintained relative to the movable electrode or latch with which it co-operates.

With the above objects in view the invention consists in what is herein shown, described and claimed.

In the drawings Figure 1 represents a side elevation of an igniter and its actuating means, the same embodying the features of my invention, parts of the igniter being 40 shown diagrammatically and in section to better illustrate the invention; Fig. 2, a detailed sectional plan view of the trip-pawl mechanism, the section being indicated by line 2—2 of Fig. 1; Fig. 3, a detailed sectional elevation of the same, the section being indicated by line 3—3 of Fig. 2; Fig. 4, another section view of the trip-pawl, the section being indicated by line 4—4 of Fig. 2, and Fig. 5, a cross-section of said pawl 45 and its connections, the section being indicated by line 5—5 of Fig. 1.

Referring by characters to the drawings, 1 represents a valve-rod that constitutes a reciprocative link, the rear end of which 50 valve-rod is connected to a valve-lever 2, the

forward end of the rod being bifurcated for engagement with a stud 3 whereby said end is supported. This stud carries the usual ignition and valve-cams, not shown, which mechanism forms no part of my invention. 60 The valve-rod or reciprocative link is provided with an ear 1' which has formed therein an elongated slot 1" for the reception of a retaining bolt 4. This bolt serves as a securing means for a trip-pawl 5 and a 65 skeleton housing 6 into which the trip-pawl is nested. The skeleton housing is formed with parallel walls 6', which walls are connected at their shank end by a web 6'' and at their outer end by a web 6''', the walls 70 being apertured adjacent to the shank for the reception of the retaining bolt 4. The trip-pawl is also provided with an apertured shank for engagement with the retaining bolt upon which it is loosely fulcrumed, the 75 free end or nose of said pawl being supported by the housing web 6'''. Thus the nose of said pawl is held in its proper position by gravity and the limit of its upward movement is checked by the engagement of the shank of the pawl with the adjacent upper edge of the housing web 6''. The housing web has extending from its inner wall, in alinement with its outer end, a lug 7, which lug rests loosely upon a stop-flange 8 that projects from the rod. 85

In attaching the trip-pawl mechanism to the rod the retaining bolt 4 is first passed through the members and its projecting threaded shank is thereafter inserted 90 through the elongated ear aperture of said rod. The housing is then drawn tightly against the inner face of said rod by a retaining nut 4' which engages the threaded end of said bolt and when the parts are so tightened the housing lug 7 is adjusted to its seat upon the stop-flange 8, in which adjustment the pawl therein assumes an oblique position with its nose clear of the afore-said housing. 95

An igniter mechanism is located in juxtaposition to the pawl, which mechanism forms no part of my present invention and is shown diagrammatically, it being understood that the movable and fixed electrodes constituting said igniter mechanism are located within or communicate with the compression chamber of a gas engine cylinder. As shown the igniter mechanism comprises 105 a spring-controlled latch member 9, which 110

latch member is mounted upon a stud 10 and has a spring tail-piece 9' extending therefrom, which tail-piece carries the movable electrode 11 that is arranged to make 5 contact with a stationary electrode 12, the same constituting one terminal of an electric circuit.

It is apparent from the foregoing description that as the valve-rod moves rearwardly 10 that the nose of the trip-pawl will engage the nose of the latch and thus close the circuit. Further travel in the same direction of the valve-rod will cause release of the spring-controlled latch, whereby the circuit 15 is broken in the usual manner and a spark produced. Should it be desired to change the time of ignition it is apparent that the retaining bolt 4 can be loosened and the housing and trip-pawl adjusted back or 20 forth within the limits of the valve-rod slot, whereby the nose of the pawl will engage the trip-latch sooner or later and in this adjustment the lug 7 which projects from the housing will ride upon the stop-flange 8 of 25 the rod, whereby the proper angle of the housing and nose of the pawl is maintained. Thus there is no complicated adjustments necessary and the parts can be readily arranged by those unskilled in the art. Owing 30 to the lack of the ordinary complicated adjustments of these parts there is slight liability of the same to become disarranged through tampering or vibration. Attention is also called to the fact that owing to the 35 stop engagement between the housing and rod that the single bolt is sufficient to support the parts rigidly as end thrust tending to twist said parts will be positively resisted by said stop, particular attention being 40 called to the fact that there can be no binding of the fulcrum pawl upon the retaining bolt, incidental to clamping engagement between the housing and rod.

I claim:

- 45 1. In an igniter mechanism; the combination of an igniter trip-latch, a rod, a double-walled housing detachably secured thereto, the housing walls being connected by a web, a trip-pawl fulcrumed between the housing 50 walls, the free end of said trip-pawl being adapted to rest upon the housing web.
2. In an igniter mechanism; the combination of an igniter trip-latch, a reciprocative rod, a housing, a trip-pawl fitted within the 55 housing, a retaining bolt for securing the trip-pawl, housing and rod together, the trip-pawl being loosely mounted upon said

bolt, and a support carried by the housing for the free end of said trip-pawl.

3. In an igniter mechanism; the combination of an igniter trip-latch, a reciprocative rod provided with an elongated slot, an apertured housing, an apertured pawl nested therein, a securing bolt in engagement with the housing aperture, pawl aperture 65 and rod slot, and a rest for the unsecured end of the housing in connection with said rod.

4. In an igniter mechanism; the combination of an igniter trip-latch, a reciprocative 70 rod provided with an elongated slot, a double-walled skeleton housing having an aperture at its shank, an apertured shank pawl fitted between the housing walls, a retaining bolt engageable with the housing 75 wall, pawl shank aperture and rod aperture, whereby the parts are held, and a stop extending from the said rod for engagement with the unsecured end of the housing.

5. In an igniter mechanism; the combination of a reciprocative rod having an elongated aperture, a skeleton housing comprising spaced side-walls having shank and end webs connecting the same, the side walls being apertured adjacent to the shank web, 85 a trip-pawl nested between the housing walls having an apertured shank, a retaining bolt fitted through the housing walls, pawl and elongated aperture of the rod whereby the members are secured together, 90 and a rest for the outer free end of the housing in connection with said rod.

6. In an igniter mechanism; the combination of a reciprocative rod having an elongated aperture, a stop extending from the 95 rod, a skeleton housing comprising spaced side walls having a shank web and an end web connecting the same, the walls being apertured adjacent to the shank web, trip-pawl nested between the housing walls having an apertured shank, a retaining bolt fitted through the housing wall apertures, pawl aperture and elongated aperture of the rod; whereby the members are secured together, the outer free end of the housing being 100 in engagement with the rod stop.

In testimony that I claim the foregoing I have hereunto set my hand at Milwaukee in the county of Milwaukee and State of Wisconsin in the presence of two witnesses. 110

HARRY W. BOLENS.
